UNITED STATES PATENT OFFICE.

ELLA MAY LICHTENSTEIN, OF NEW YORK, N. Y.

TOILET-POWDER BOX.

SPECIFICATION forming part of Letters Patent No. 697,729, dated April 15, 1902.

Application filed October 25, 1901. Serial No. 79,887. (No model.)

To all whom it may concern:

Be it known that I, ELLA MAY LICHTENSTEIN, a citizen of the United States, and a resident of the city of New York, borough of Manhattan, county and State of New York, have invented certain new and useful Improvements in Toilet-Powder Boxes, of which the following is a specification.

This invention relates to boxes for holding 10 toilet powders which can be used as an original package for the powder during storage, shipment, &c., and as a toilet box for the powder when in use.

The invention resides in the novel construction and combination of parts herein-after described, and finally pointed out in the claims.

In the drawings forming part of this specification, Figure 1 is a side elevation of a conventional box, otherwise constructed in accordance with my improvements. Fig. 2 is a sectional elevation centrally thereof on the plane of the line 2 2, Fig. 1. Fig. 3 is a plan view of the distributing-diaphragm; and Fig. 25 4 is a sectional elevation on the line 4 4, Fig. 3.

Similar reference characters represent corresponding parts throughout the several views.

The object of my invention is to provide a 30 box which not only can be used to hold the contained toilet powder or similar substance for storage and shipment, but which will essentially provide means for preventing undue loss or extravagant use of the powder.

For holding toilet powder it has been customary to provide boxes in which the powder is contained, in which also is placed a "puff" or similar article, which is adapted to carry with it upon removal considerable of the contained powder and which permits of its being distributed upon the person of the user.

Another way has been to employ a chamois or other cloth, which has been inserted in the powder, removing a quantity thereof for application to the person. Both of these and other like methods of use result in not only unnecessarily distributing the powder, but in extravagantly removing the same. In other words, more has been removed from the 50 box than is essential for the requirements of its use. To avoid this, various forms of toilet boxes have been devised, none of which,

however, have, so far as I know, either from cost of manufacture or complexity of construction, are adapted to act both as an original package for storage and shipping the powder and as a toilet box. These devices have comprised, essentially, suitably-constructed boxes having a horizontally-disposed and stationary (relative to vertical movement) partition, notable examples of these boxes being found in the patents to W. Hill, No. 472,217, dated April 5, 1892, and C. P. Thomas, No. 520,343, dated May 22, 1894. In the former patent a partition is provided 65 having a central opening defined by downwardly-extending projections which rest at all times upon the bottom of the box. In the latter patent the box is provided with a hemispherical partition secured interiorly in the 70 box at a distance above the bottom of the box and provided with apertures extending throughout the entire surface exposed to the space below it. In neither of these structures is the partition movable vertically. In 75 neither of them is it movable to follow the powder down as it is used. In neither of them is the partition thin and flexible, so that by slightly tapping the same the powder will be forced through apertures centrally disposed 80 or grouped with relation to the partition. In neither of them are found centrally-grouped apertures located in the flat portion of the partition, so as to admit of a further fine distribution of the powder ejected from below 85 by dispersing it with a cloth or finger thereon and obtaining a thin film of powder for application to the person, and in neither of these structures is found a cheap and simple package adapted in any way to form an original 90 package and the toilet article.

The foregoing states the results obtained and the improvements from which they flow.

By reference to the drawings, which disclose an embodiment of my invention, 1 is a 95 box of conventional construction, of paper or any other desired material; 2, the bottom; 3, the walls, and 4 a conventional cover therefor. I prefer that this box be circular, as shown, although it may be found advantageous to employ other forms; but I do not limit myself to any particular shape or construction of box herein shown.

At 5 is the partition or diaphragm, (specif-

ically circular,) and 6 the powder therein, diagrammatically illustrated. The partition or "diaphragm," as I prefer to call it, is made of a thin flexible sheet of paper or other desirable material, sufficiently flexible to allow of its being downwardly distorted by light pressure, and which should fit the interior of the box substantially snugly, but with sufficient clearance to permit it to either fall of 10 its own weight with the consumption of the powder or be caused to follow the same downwardly by slight pressure. I prefer that the fit of the diaphragm in the box be such as to not permit the powder being forced up between its periphery and the inner walls of 15 the box; but if this occurs it will not be material, as the escape of the powder at that point will be comparatively small, it being intended that the ejection come from the center. The diaphragm is further provided with 20 perforations 7, which are preferably small and elongated (though not essentially so) and which are grouped together and located centrally (preferably) of the diaphragm with reference to its periphery.

In use the loose fit of the diaphragm in the box or slight pressure thereon will cause it to follow the powder down as it is used and by 25 slightly tapping or flexing the diaphragm, preferably over the apertures, with the finger or the cloth by which the powder is to be applied the latter will be forced through the apertures (as in Fig. 2) either directly onto the cloth or out upon the top of the diaphragm, from whence it can be directly applied upon 30 the person or spread out thinly before doing so.

By means of the foregoing construction the powder can be put in the box, stored, transported for sale as an original package, and 35 finally employed as toilet box. The powder can be more equally distributed for immediate use and its extravagant use or loss

avoided, the movable diaphragm permitting all of the powder to be used without shaking or disturbing the box.

45

Having described my invention, I claim—

1. In an article of the class described, the combination with a box, of a thin and flexible diaphragm loosely fitting the interior of the box, and provided with a plurality of centrally-grouped apertures, whereby the diaphragm is adapted for being flexed to eject the comminuted contents through the centrally-grouped apertures, substantially as described.

2. The combination in an article of the class described, of a box comprising a circular body, a cover therefor, and a circular diaphragm loosely fitting the interior of the box, and adapted to be moved to the bottom 60 thereof, said diaphragm being made of thin flexible material, and provided with a plurality of apertures centrally grouped with reference to the periphery thereof, whereby the diaphragm is adapted for being flexed to 65 eject the comminuted contents through the centrally-grouped apertures, substantially as described.

3. In an article of the class described, the combination with a box, of a thin, flat and 70 flexible diaphragm loosely fitting the interior of the box, and provided with a plurality of apertures grouped at the central and flat portion thereof, whereby the diaphragm is adapted for being flexed to eject the comminuted 75 contents through the centrally-grouped apertures, substantially as described.

Signed in the city, county, and State of New York this 22d day of October, 1901.

ELLA MAY LICHTENSTEIN.
